UNITED STATES PATENT OFFICE.

MOE J. WEISBURD, OF NEW YORK, N. Y.

ARTIFICIAL FUEL.

No Drawing.

Application filed June 23, 1925. Serial No. 39,149.

To all whom it may concern:

Be it known that I, MOE J. WEISBURD, a citizen of Russia, residing in the city of New York, borough of Bronx, in the county of Bronx and State of New York, have invented a certain new and useful Improvement in Artificial Fuels, of which the following is a specification.

The invention relates to combustible com-
10 pounds used as substitutes for coal, and the object of the invention is to provide an inexpensive easily manufactured compound of this character adapted to be used in ordinary types of stoves and furnaces in conjunction
15 with coal.

The invention consists in compounding certain waste materials in certain proportions, by which the above objects are attained, to be hereinafter described and
20 claimed.

The materials employed are coal ashes and the waste lubricating oils drained from motor vehicles. In carrying out the invention with the best results, as indicated by my
25 experiments, I take two-thirds of a barrel of finely sifted coal ashes contained in a suitable receptacle, and add one gallon of spent motor-oil poured thereon and thoroughly mixed therewith. This composition
30 is allowed to stand about forty-eight hours and is well stirred several times during that period.

The result is a viscous mass having the fluidity of warm tar, and is capable of flowing slowly when poured or it may be handled with a shovel or like implement. It may be stored and delivered in boxes, barrels and like containers or in strong cartons.

In using the manufactured fuel to the

best advantage, the fire is started in the 40 stove or furnace in the usual manner and coal supplied to produce a bed of hot coals about three inches in depth, the compound is then placed upon such bed to a depth of about three inches evenly distributed, and 45 this layer again covered with about three inches of coal. The compound burns freely with the coal and the fire is maintained continuously by supplying alternate layers of 50 the compound and coal.

Any usual type of grate may be employed and bituminous coal may be used and is preferred, the heating effect produced by combustion with the compound being practically that of anthra- 55 cite coal, thus effecting a great saving especially in domestic cooking and heating plants, which may be expressed as the difference in cost between one ton of the compound and one ton of soft coal, and that of 60 three tons of hard coal, and as soft coal is comparatively low in cost and the materials of the compound wholly waste products involving only the labor-cost of collecting, 65 mixing, and delivering to the consumer, the saving is considerable.

I claim:

The artificial fuel compound described consisting of finely sifted coal ashes and spent crank case lubricating oil, in the ap- 70 proximate proportions of substantially two bushels of such ashes to one gallon of the oil, and thoroughly mixed to produce a homogeneous semifluid mass and adapted to be applied upon a previously-lighted fire. 75

In testimony that I claim the invention above set forth I affix my signature hereto.

MOE J. WEISBURD.
